UNITED STATES PATENT OFFICE.

JOSEPH B. HOLDEN, OF SYRACUSE, NEW YORK, ASSIGNOR TO REMINGTON TYPE-
WRITER COMPANY, OF ILION, NEW YORK, A CORPORATION OF NEW YORK.

TYPEWRITING MACHINE.

Application filed November 13, 1924. Serial No. 749,579.

My invention relates to typewriting or like machines and more particularly to the paper feed mechanism thereof.

The main object of my invention, generally stated, is to provide simple paper feed releasing means which are inexpensive to manufacture, are highly efficient in use, are easy to assemble in the machine or replace, and are not liable to become injured or broken.

To the above and other ends which will hereinafter appear, my invention consists in the features of construction, combinations of devices, and arrangements of parts hereinafter described and particularly pointed out in the appended claims.

In the accompanying drawings, wherein like reference characters indicate corresponding parts in the different views,

20 Figure 1 is a detail fragmentary rear elevation of the carriage of a Remington portable machine equipped with the devices of my invention, and with parts omitted.

Figure 2 is a detail fragmentary top plan view of the same.

Figure 3 is an enlarged detail fragmentary transverse sectional view taken on the line 3-3 of Fig. 2 and looking in the direction of the arrows at said line.

30 Figure 4 is a like view taken on the line 4-4 of Fig. 2 and looking in the direction of the arrows at said line.

Figure 5 is an enlarged detail perspective view of the holding spring for the releasing means shown detached.

Figure 6 is a detail perspective view of the floating feed roll releasing member shown detached and with the spring removed therefrom.

40 Figure 7 is an enlarged detail transverse sectional view taken through the carriage on the line 7-7 of Fig. 2 and looking in the direction of the arrows at said line; this view showing the parts as they appear when the feed rolls are applied.

Figure 8 is a like view of the same except that the parts are shown disposed as they appear when the feed rolls are locked off.

Figure 9 is a fragmentary detail top plan view of certain of the parts shown in Fig. 7, disposed as the parts appear in said figure.

Figure 10 is a like view of the same showing the parts as they are disposed in Fig. 8.

I have shown my invention embodied, in

55 the present instance, in a Remington port-

able machine, in which the invention may be readily incorporated with but little change. It should be understood, however, that the invention is not restricted to embodiment in such machine but may be employed in typewriting or like machines generally, wherever found available.

The present construction is in the nature of an improvement on those disclosed in my Patent No. 1,458,133 dated June 12th, 1923, 65 in my application Sr. No. 723,489 filed July 1, 1924, and in the application of Herbert E. Bridgwater, Sr. No. 729,225, filed July 31, 1924.

The carriage of the Remington portable 70 machine comprises a main body plate 1 provided with end plates 2 each formed with a foot piece 3 by which it is secured to the body portion 1 of the carriage. The end plates are provided with bearings to receive 75 a platen spindle 4 on which the platen 5 is mounted. The usual paper apron has been omitted to avoid confusing the illustration.

Bracket plates 6 are secured by screws 7 to the upper side of the body plate 1 of the 80 carriage, and each of said plates 6 is formed with rear bearings 8 and front bearings 9. The rear bearings receive pivot rods 10 that also extend through bearings 11 on a feed roll support or carrier 12 that extends longitudinally substantially throughout the length of the platen. The carrier 12, which is thus pivotally mounted on the carriage to swing towards and away from the platen, is in the nature of a comparatively thin sheet 90 metal strip or plate. For reasons which will hereinafter appear it was found necessary heretofore to strengthen this strip 12 by a reinforcing channel bar of sheet metal, sub-

stantially U-shaped in cross section, which 95 was secured to the strip 12 at the front side thereof and extended longitudinally substantially throughout the length of said strip. By my present invention I am enabled to dispense with this reinforcing bar, for rea- 100 sons which will presently appear. Loosely connected at 13 to the carrier 12 are two roll holders 14. Feed rolls 15 are mounted in each holder at opposite sides of the associat- 105 ed point of connection 13, and each holder is guided for fore-and-aft teetering move- ment on its connection 13 by guide finger 16, as disclosed in my application Sr. No. 723,489 hereinbefore referred to.

The bar feed roll carrier 12 is formed at 110

each side of the middle thereof with a forwardly extending integral projection or arm 17. A wire spring 18 is fastened at its center in bearings in a block 19, secured by screws 20 to the carriage plate 1 about midway in the length thereof. Each end portion of this spring bears down on a projection 17 tending to turn the feed roll carrier 12 on its pivots 10 and move the rear feed rolls 15 against the platen, or the paper thereon.

Forward feed rolls 21 are mounted in a sheet metal carrier 22 provided with bearings 23 to receive pivot rods 24; said pivot rods being supported in the forward bearings 9 on the bracket plates 6. In this manner the forward set of feed rolls 21 is pivotally mounted to swing fore-and-aft of the machine into and out of contact with the platen, or the paper thereon. Rearwardly projecting arms 25 are formed integral with the carrier 22, and extend over the arms 17 and beneath the free end portions of a spring 26 parallel with the spring 18 and secured in a like manner to the block 19. The spring 26 tends to force the forward feed rolls against the platen.

The parts as thus far described may be of the usual construction.

In order to release the feed rolls 15 and 21, and if necessary lock or hold them in the released position as shown in Fig. 8, I provide the following construction:—The block 19, fixed to the carriage midway in the length thereof, is provided with upstanding projections 27 which constitute a fixed abutment with which the releasing device co-acts, as will presently appear. Interposed between the rear face of this abutment and the forward face of the feed roll carrier 12 is a releasing or controlling or actuating member which in the present instance is in the nature of a block or bar 28 angular in cross section. This bar 28, as will be seen from an inspection of Fig. 3 is located about centrally of the pivoted roll carrier 12 and extends, in the present instance, longitudinally thereof to about the points where the spring 18 exerts its force against said carrier 12 through the arms 17. The left-hand end of the angular bar is reduced to form a bearing stud 29 which is received in an open-mouthed substantially horizontally disposed bearing slot 30. As best shown in Fig. 4, this bearing slot is formed in a bracket 31 which has its foot piece 32 riveted at 33 to the carrier 12. A corresponding bracket 34 (see Fig. 3) is secured by screws 35 to the right-hand end of the carrier 12 to aid in supporting and guiding the releasing device. The part 28 may be regarded as a part of or a cam or enlargement on a rock shaft 36. For manufacturing purposes, however, I prefer to make the parts 28 and 36 from separate pieces and unite them by providing a hole

in the right-hand end of the member 28 to receive the inner end of the rock shaft 36, as indicated in Fig. 2. The two parts may then be fixedly united by spot welding or otherwise. The outer end of the shaft 36 extends to the end of the carriage where it is bent to form a crank arm 37 provided with a finger piece 38. Said finger piece enables the operator to rock the shaft, and the member 28 forming part thereof, from the Fig. 7 to the Fig. 8 position, or vice versa.

A stop pin 39 projects inwardly from the right-hand end plate 2 of the carriage and co-acts with the crank arm 37 to limit the rocking movement of the releasing member 28 when it reaches the Fig. 8 position. The part 28 is tapped at 40 (see Fig. 6) in its forward face and about midway in the length thereof. The stem of a headed screw 41 is received in this tapped opening after passing through a centrally located opening 42 in a spring member 43, shown in detail in Fig. 5. This member is in the nature of a bowed leaf spring flexed forwardly from the screw 41 to the ends of the spring. At each end the spring is provided with ears 44 that extend rearwardly and loosely embrace the part 28 on the top and bottom sides thereof. This prevents the spring from turning on the screw 41 by which it is fastened to the member 28, but said ears also have another function, as will presently appear. It will be understood that the spring 43 is of relatively hard metal having a smooth surface and is interposed between the part 28 and the contact faces of the abutment 27. In the back and forth rocking movements of the member 28, between the Figs. 7 and 8 positions, wear will not be on the relatively soft part 28 but will be between the abutment 27 and the forward face of spring 43 and the lower ears 44 thereon where they join the body portion of the spring. When the parts are in the normal position, shown in Figs. 7 and 9, the spring 43 will bear against the abutment 27 and the force of the spring will be exerted to hold the member 28, and the rock shaft 36 forming part thereof, against loose turning movement, and also against a fore-and-aft bodily floating movement in the guide brackets 31 and 34. However, the power of this spring, while sufficient for the purpose stated, is ineffective to overcome the power of the springs 18 and 26 by which the feed rolls 15 and 21 are pressed against the platen.

In the operation of the releasing device, the first part of the movement thereof from the Fig. 7 to the Fig. 8 position results in compressing the flexed ends of the spring 43 against the front face of the part 28. When the spring 43 has been thus compressed further turning of the rock shaft and its member 28 will cause the latter to operate with a camming action against the abutment

27. This results in effecting a slight lateral or rearward bodily floating movement of the part 28-36 in its guides, as well as a turning movement, thereby causing the roll carrier 12 to turn on its pivots 10 and to move the feed rolls 15 away from the platen. This causes an upward movement of the arms 17 against the force of the spring 18, at the same time carrying the arms 25 up 10 against the force of the spring 26, thereby releasing the forward feed rolls 21.

When the releasing device has been shifted to the full extent of its releasing movement, shown in Figs. 8 and 10, it will be seen that opposite angular corners of the members 28 are disposed substantially horizontally, and the full extent of camming off action has been attained. It also will be seen that at this time the force of the springs 18 and 26 exerted through the carrier 12 is dead centered against the fixed abutment 27, thus holding the parts in the released position indefinitely, or until the shaft is rocked in the opposite direction by the finger piece 38.

In assembling the parts it is merely necessary to mount the single member 28-36-37-38 in place by introducing it through the open-mouths into the bearing slots in the brackets 31 and 34. When thus mounted in place, with the spring 43 bearing against the abutment 27, said member will be held against movement longitudinally of the carriage in one direction by the shoulder where the body joins the reduced end 29 bearing against the bracket 31. Said member is held against movement in the opposite direction by the crank arm 37 co-acting with the inner face of the right-hand end plate 2 of the carriage.

The releasing mechanism is simple, strong, durable and effective in use and is not liable to be injured or broken. However, should the above mentioned member require removal or replacement, for any reason, this may be quickly effected.

The centering of the application of power to simultaneously and uniformly release all feed rolls in the manner disclosed herein is an important factor. Thus it will be understood that by overcoming the resistance of the springs of the carriers 12 and 22 and releasing the feed rolls by force directed against said carriers centrally in the lengths thereof, instead of at one end only, as in the previous constructions referred to, a more effective release of the feed rolls may be brought about without liability of bending or straining the comparatively light sheet metal from which said carriers are made, and without reinforcing and strengthening the parts to render the release effective.

By extending the part 28 to the points where the power of the springs 18 and 26 is applied to the member 12, and causing said

member to bear against the comparatively light sheet metal member 12 throughout the distance between these points, I am enabled to make the member 12 of light unreinforced metal, without liability of bending 70 the carrier in forcing it to releasing position and cause all of the rolls to be simultaneously released and applied.

These features while important in any typewriter are of particular importance in 75 a portable machine in which it is advantageous, if not absolutely essential, to make the compactly arranged parts as light as possible consistent with efficiency of operation.

From what has been said it will be understood that the devices of my invention can be easily embodied in Remington portable machines without materially changing existing structural features thereof.

What I claim as new and desire to secure by Letters Patent is:—

1. In a typewriting or like machine, the combination of a carriage, a platen carried thereby, a series of feed rollers that extend longitudinally of said platen, a pivoted sheet metal carrier that extends substantially throughout the length of the platen and on which said series of feed rollers is mounted, springs which apply their force 85 to said carrier and through it to the series of feed rollers and cause the latter to bear against the platen or the paper thereon, and releasing means for moving said carrier without bending it, in order to simultaneously release all of the feed rollers of said series, said releasing means comprising a floating rock shaft having a camming portion that extends longitudinally of the carriage to the point of resistance of said 100 springs, and a fixed abutment on the carriage about midway in the length thereof and between which abutment and carrier the camming portion of the shaft is received to coact with the carrier about midway in 110 the length thereof and at about the points where the resistance of said springs is exerted against the carrier, in order to move the carrier without bending it and thus simultaneously release the feed rollers. 115

2. In a typewriting or like machine, the combination of a carriage, a platen, a rock shaft that extends longitudinally in the direction of the travel of the carriage, slotted guides on the carriage that receive said 120 shaft and permit it to have a back and forth movement in one direction as well as a turning movement, an abutment fixed on the carriage, an actuating member carried by said shaft about midway in the length of the 125 carriage and having a camming action against said abutment when the shaft is turned in one direction thereby effecting a lateral shifting of said actuating member and shaft, a feed roll carrier that extends 130

- substantially throughout the length of the platen, a series of feed rollers that extend longitudinally of the platen and that are carried by said carrier, said carrier being controlled by a shifting movement of said actuating member, and a finger piece formed on one end of said rock shaft for turning it.
3. In a typewriting or like machine, the combination of a carriage, a rock shaft that extends longitudinally in the direction of the travel of the carriage from near one end thereof beyond a point midway in the length of the carriage, slotted guides on the carriage that receive said shaft and permit it to have a back and forth lateral movement in one direction as well as a turning movement, an abutment fixed on the carriage, a spring-pressed feed roll carrier, an angular block-like actuating member fixed to said shaft about midway in the length of the carriage and interposed between said carrier and abutment, said member having a camming action on the abutment to shift the actuating member and shaft laterally and thus shift the roll carrier with which said member also co-acts against the force of its spring, the construction and arrangement of the parts being such that said member is substantially dead centered against the action of the spring pressure of the roll carrier when the shaft is turned the limit of its movement in one direction to hold and maintain the feed rolls released, a finger piece for turning said rock shaft, and a spring which co-acts with said shaft to prevent loose movement thereof when the shaft is in normal position.
4. In a typewriting or like machine, the combination of a carriage, a platen carried thereby, a fixed abutment on the carriage, a feed roll carrier that extends substantially throughout the length of the platen, a series of feed rollers that extend longitudinally of the platen and that are carried by said carrier, springs that act on said carrier to force the feed roll against the platen, a rock shaft that extends longitudinally of the carriage between said carrier and abutment, and an actuating member on said shaft that is disconnected from but coacts with said abutment and carrier to shift the feed rolls off by a camming action, said actuating member extending longitudinally of said shaft to the points of resistance of said springs against the feed roll carrier but free from the resistance of said springs when the latter press the feed rollers against the platen.
5. In a typewriting or like machine, the combination of a carriage, a platen, a fixed abutment on the carriage about midway in the length thereof, a feed roll carrier that extends substantially throughout the length of the platen, a series of feed rollers that extend lengthwise of the platen and which are carried by said carrier, springs that act on said carrier between the ends of the carriage and a point midway in the length thereof and apply their force through the carrier to the said series of feed rollers, and a hand controlled actuating member interposed between and disconnected from said abutment and carrier but coacting therewith when turned in one direction to move said carrier and release the said series of feed rolls, said actuating member contacting with said carrier intermediate the points where said springs exert their force against the carrier.
6. In a typewriting or like machine, the combination of a carriage, a platen, a fixed abutment on the carriage about midway in the length thereof, a spring-pressed feed roll carrier, a floating hand operated actuating member interposed between said abutment and carrier to shift the carrier and release the feed rolls when turned in one direction, said actuating member being normally free from the pressure of the spring or springs of said carrier, and a spring of less power than that of the spring or springs of said carrier for holding the floating actuating member against free motion when the feed rolls are applied to the platen or the paper thereon.
7. In a typewriting or like machine, the combination of a carriage, a platen, a fixed abutment on the carriage, a spring-pressed feed roll carrier, a floating hand operated actuating member interposed between said abutment and carrier and operative to cam off the carrier and feed rolls when turned in one direction, and a relatively light spring constituting a contact face between said actuating member and abutment and tending to hold said actuating member against free movement when the feed rolls are applied.
8. In a typewriting or like machine, the combination of a carriage, a platen, a fixed abutment on the carriage, a spring-pressed feed roll carrier, a floating hand operated actuating member interposed between said abutment and carrier and operative to cam off the carrier and feed rolls when turned in one direction, and a relatively light bowed leaf spring secured to said actuating member and constituting a contact face between the latter and said abutment, said leaf spring also tending to hold said actuating member against free movement when the feed rollers are applied.
- Signed at Syracuse, in the county of Onondaga and State of New York, this 7 day of November, A. D. 1924.
- JOSEPH B. HOLDEN.
